MOBILE SUPPORT FOR FLEXIBLE POWER
SUPPLYING ELEMENTS

William S. Chapin, Jr., Muskegon Heights, Mich.,
assignor to Manning, Maxwell & Moore, Inc.,
Muskegon, Mich., a corporation of New Jersey

Application February 23, 1949, Serial No. 77,966

1 Claim. (Cl. 191—12)

1

The invention relates to traversing hoists and comparable power-driven apparatus adapted to travel on overhead runways or tracks and to receive its power supply by way of a flexible element such as a conductor cable or an air hose, and it is more particularly concerned with means for supporting and taking up slack in the flexible element by which power is supplied to the apparatus.

One object of the invention is to provide improved means of the above general character operative to support the flexible power supplying element in an out-of-the-way position and to keep it free of objectionably sharp bends or kinks in all positions of the traveling apparatus while subjecting the element to a minimum of tensional or other strains, and which is adapted for use with either straight or curved tracks and capable of maintaining the flexible element substantially aligned with the track when used with the latter.

Another object is to provide supporting means utilizing a series of mobile carriers adapted to grip the flexible element at relatively short intervals and operating on the apparatus supporting track, thereby avoiding the necessity of installing auxiliary tracks or guide wires with their added space requirements and extra costs.

Still another object is to provide an improved mobile carrier unit for supporting flexible power supplying elements which is universally adjustable for use with overhead tracks of any size commonly employed, which can be installed quickly and easily in existing track systems, and which is very simple in construction and inexpensive to manufacture.

Other objects and advantages of the invention will become apparent from the following detailed description of the preferred embodiment illustrated in the accompanying drawing, in which:

Figure 1 is a fragmentary perspective view of a traversing hoist installation equipped with power element supporting means embodying the features of the invention.

Fig. 2 is a perspective view of one of the mobile carrier units of the supporting means.

Fig. 3 is an end view of the mobile unit showing it adjustable for operation on a conventional overhead hoist track.

While the invention is susceptible of various modifications and alternative constructions, I have shown in the drawings and will herein describe in detail the preferred embodiment, but it is to be understood that I do not thereby intend to limit the invention to the specific form

2

disclosed, but intend to cover all modifications and alternative constructions falling within the spirit and scope of the invention as expressed in the appended claim.

For purposes of illustration the invention has been shown as supporting a flexible power supplying element in the form of a conductor cable 5 supplying power to an electrically-operated hoist 6. The hoist shown is of the conventional type and is suspended by a hook 7 from a carriage or trolley 8 adapted to run on an overhead track formed by a beam 10. The beam 10, as shown, is a conventional I-beam having opposed laterally projecting flanges 11, the lower ones of which constitute the track for the carriage 8. In practice the beam is suspended in a horizontal elevated position and may be either straight or curved as required by the particular environment in which it is installed.

The trolley 8 shown by way of illustration comprises a pair of triangular side members 12 arranged in inverted positions and connected at their lower corners by a cross bolt 13 to which the hook 7 of the hoist may be attached. Each side plate carries a pair of inwardly projecting studs 14 upon which are journaled flanged wheels 15 engageable with the beam flange 11 forming the hoist track.

In the exemplary embodiment of the invention, the power cable 5 is connected at one end to the hoist 6 and at the other end to a suitable source of electric current, as, for example, the electrical system of the shop or building in which the hoist is installed. The latter end of the cable, that is the end remote from the hoist, is also anchored to the building wall or other stationary structure adjacent one end of the track. It will be understood of course that the cable 5 is of approximately the same length as the track so as to allow the hoist trolley to traverse the full length of the track.

In accordance with the invention, the cable 5 is supported at relatively short intervals along its length by a series of mobile carriers 16 adapted to run on the same track as the carriage 8, that is, on the flanges 11 of the beam 10. With this arrangement the carriers are pushed together into a compact group by the trolley 8 as it approaches the end of the track at which the power cable is anchored and are drawn along in succession by the trailing cable as the trolley moves toward the other end of the track. The cable is secured to each carrier by means of a clip 17 mounted to permit swiveling movement about a vertical axis, whereby the cable may be gathered

in a series of relatively small, closely spaced loops disposed generally transversely of the track as the carriers come together. This allows the carriers to be moved into closely packed relation without producing sharp bends or kinks in the cable and the latter can straighten out without kinking as the carriers are spread apart. Dead space at the end of the track is thus reduced to a minimum.

The carriers 16 are all alike and are constructed so that they may be produced cheaply by simple die-forming and stamping operations. To simplify manufacture and installation and to afford a wide range of adjustability for tracks of different widths, the carriers are preferably constructed of two similar, generally L-shaped members having horizontal legs 20 and upright legs 21. These L-shaped members are assembled with their horizontal legs 20 secured together in overlapping relation and their upright legs 21 of the members are spaced apart laterally to straddle the track beam 10. Legs 21 carry wheels or rollers 22 adapted to run on the flanges 11 of the track beam to afford easy movement of the carriers along the track.

To provide adjustability, the overlapping legs 20 of the frame members are secured together by bolts 23 extending through longitudinally disposed slots 24 formed in the legs. By loosening these bolts, the frame members can be shifted toward or from each other to space the rollers for proper engagement with the flanges of the beam of any width commonly used for hoist tracks. The bolts when tightened up retain this setting permanently.

The adjustable construction above described is also advantageous in the installation of the carriers. Thus the frame members may be spread apart sufficiently to allow the rollers 22 to be slipped over the track flange at any point along the beam and the members may then be adjusted to proper spaced relation and rigidly clamped together.

Preferably the frame members are initially constructed with their horizontal legs 20 of a length such as to allow spacing of the rollers 22 sufficiently to cooperate with the flange of a track beam of the maximum width ordinarily employed for supporting hoists and comparable electrical apparatus. When a carrier is used with a relatively narrow track beam, the end portions of the horizontal legs 20 may be shortened to the extent required by removing a section therefrom. To facilitate such removal, the edges of the legs 20 are notched as at 25 to define a series of break lines spaced progressively from the ends of the legs.

To provide lateral clearance for the carrier, the frame members are formed so as to present the rollers 22 in inwardly spaced relation to the upright legs 21 of the members. For this purpose the upper end portion 26 of each leg 21 is offset inwardly from the leg. A suitably bushed screw 27 anchored in the end portion 26 serves as a shaft for the roller 22. When intended for operation with beams having tapered flanges, the roller-supporting portions 26 of the frame members are inclined outwardly, as shown in Figs. 2 and 3, so as to locate the screws 27 and the axes of the rollers 22 parallel to the bearing surfaces presented by the flanges.

Provision is made for preventing direct contact between the rollers 22 of the several carriers and between the roller of the end carrier of the group and the adjacent wheel 15 of the

trolley 8 when the carriers are being pushed along the track by the trolley. For this purpose each roller 22 is provided with a guard 30 which may conveniently comprise an elongated flat metal bar secured to the upright leg of the frame member and having inwardly turned flanges 31 projecting at diametrically opposite sides of the roller. As the carriers come together these flanges engage each other as shown in Fig. 1, while the rollers remain separated and therefore free to turn with a minimum of friction.

As shown in Fig. 1, wheel guards are also provided on the trolley 8. These guards may conveniently comprise flat bars 32 supported on the side plates 12 of the trolley frame so as to project toward the carriers 16. A flange 33 at the outer end of each bar 32 extends inwardly to overlie the adjacent wheel trolley 15 and engage the guard flange 31 on the carrier roller guard nearest the trolley. Direct contact between the trolley wheels and carrier rollers is thus prevented.

The clip 17 by which the cable 5 is connected to the carrier may be of any suitable construction. As herein shown the clip is constructed from a flat strip of resilient metal bent to provide a pair of laterally spaced cable-gripping fingers 35 connected at their upper ends by an integral crosspiece 36. The lower ends of the fingers are preferably bowed to conform generally to the contour of the cable and are adapted to be drawn together to clamp onto the cable by means of a clamping bolt extending through suitable apertures intermediate the ends of the fingers.

To afford the swiveling action required for the efficient coiling and uncoiling of the cable loops, the clip 17 is secured to the carrier 16 by means of a headed bolt 38 projecting through a clearance hole in the crosspiece 36 and through the aligned slots 24 in the overlapping legs of the carrier frame members. By reason of its reception in the slots, the bolt may be adjusted transversely of the carrier to locate the clip in vertical alignment with the track upon which the carrier is supported. Nuts 39 threaded on the bolt on opposite sides of the legs 20 secure the bolt in adjusted position.

In practice, sufficient carriers are provided to support the cable at relatively short intervals so that the intervening cable section is held out of the way of persons working under or passing below the track. As the trolley 8 approaches the end of the track adjacent which the cable 5 is anchored, the guards 33 engage the corresponding guards 31 of the first carrier and push it along. Succeeding carriers, in turn, are engaged progressively until all are pushed into a compact group at the end of the track. Due to the swivel mounting of the cable-gripping clips 17, the cable is permitted to swing so that the loops between adjacent clips are disposed generally transversely of the track. This eliminates sharp bends or kinks in the cable and reduces to a minimum the space required at the end of the track for accommodation of the cable and associated carriers.

As the trolley 8 moves toward the other end of the track, the cable 5 trails along and pulls the carrier 16 ahead progressively until the cable is fully extended. Here again the swiveling actions of the clips 17 are advantageous in allowing the cable to straighten out without kinking. The rollers provided on the carriers and the guards associated therewith assure free movement of the

carriers at all times, thus minimizing tensional or other strains on the cable.

I claim as my invention:

A mobile carrier for supporting the flexible power supplying element of power-driven apparatus mounted on a carriage operating on an overhead track, said carrier having a frame comprising a pair of L-shaped members assembled with their horizontal legs in overlapping relation and secured together by through bolts, said horizontal legs being slotted longitudinally to accommodate said bolts and permit relative shifting of the members for varying the spacing of their upright legs, an element-gripping clip, and means securing said clip to the assembled members, said securing means engaging in said slots and being adjustable therein into centered relation with respect to the upright legs of the members.
